UNITED STATES PATENT OFFICE.

JESSE E. PALMER, OF LOS ANGELES, CALIFORNIA.

BLOTTER-HOLDING DEVICE.

Application filed March 24, 1922. Serial No. 546,212.

To all whom it may concern:

Be it known that I, JESSE E. PALMER, a citizen of the United States, residing at Los Angeles, in the county of Los Angeles and State of California, have invented new and useful Improvements in Blotter-Holding Devices, of which the following is a specification.

My invention relates to blotter holding devices, and a purpose of my invention is to provide a device of this kind which is adapted for attachment to the wrist and in such position that the writer can frequently and conveniently blot his writing with the writing hand, my invention being particularly adapted for bookkeepers and the like.

Although I will describe only one form of blotter holding device embodying my invention and point out the novel features thereof in claim, it is to be understood that various changes and modifications may be made herein without departing from the spirit and scope of such claim.

In the accompanying drawings, Figure 1 is a view showing one form of blotter holding device embodying my invention in applied position upon a wrist.

Fig. 2 is a top plan view of the device shown in Fig. 1.

Fig. 3 is a bottom plan view of the blotter holding device.

Fig. 4 is a view showing the blotter holding device in edge elevation, the view being taken looking downwardly as indicated by the arrow 4 in Fig. 5.

Fig. 5 is a central sectional view taken on the lines 5—5 of Figs. 3 and 4, and looking in the direction indicated by the arrows.

Similar reference characters refer to similar parts in each of the several views.

Referring specifically to the drawings, my invention, in its present embodiment, comprises an arcuately curved plate designated at P and having formed on its convex or lower side a plurality of bendable clips 15 which are adapted for removably retaining a blotter B thereon. The upper or con-

cave side of the plate P is provided with a concave disc-shaped head H which, as clearly shown in Fig. 5, is arranged in diverging relation with respect to the plate so as to cause the latter to occupy the proper position for blotting when the device is in applied position upon the wrist.

At spaced points upon the periphery of the head H, perforated ears E are secured, with one of these ears receiving the end of an elastic strap D, while the opposite end is adapted to removably receive a hook K attached to the free end of the strap.

In the applied position of the device as shown in Fig. 1, the strap serves to secure the head H in contiguous relation with respect to the base of the palm and directly in advance of the wrist joint. In this position of the head, the plate P and consequently the blotter B is so held that when advancing the hand in blotting, the blotter will lie flat transversely upon the paper so that when rocking the wrist a corresponding movement is imparted to the blotter to cause its entire surface to engage the paper.

From the foregoing manner of application, it will be manifest that the device does not interfere with the normal position and movement of the hand in writing, and that the writing hand can be employed in effecting a blotting of the writing and without releasing the pen. This obviously eliminates the necessity of using the writing or the other hand in blotting as is now the present practice.

What I claim is:

A blotter holding device comprising an arcuately curved plate to receive a blotter, means to secure the blotter in place, the back of the plate being provided with a disc-like palm rest having a concaved face to receive the contiguous part of a palm when the device is applied to a writer's hand, and a strap for fastening the device to the hand.

In testimony whereof I have signed my name to this specification.

JESSE E. PALMER.
